WINDOW CONSTRUCTION

Stephen M. Casey, Oakland, Calif.

Application April 8, 1955, Serial No. 500,153

2 Claims. (Cl. 189—72)

This invention relates to a new and useful window construction and particularly to a resilient window sash suspension including novel weather stripping means.

The invention includes a plurality of sash supporting members which may be fitted or secured to a window opening in a given structure. The supporting members include means whereby window sashes may be resiliently suspended therein. Also the various components are formed to fit snugly to provide a substantially weather tight unit when assembled.

A particular object and feature of this invention is the provision of weather stripping formed integral with one sash and disposed between the horizontally spaced sashes whereby the closed windows are weather tight at the point of juncture.

Another object of the invention is to form the top and bottom sash supporting members to receive the sashes in a snug and weather tight manner and to provide effective weather stripping at the top and at the bottom of the installation of windows.

Also, an object of this invention is the provision of supporting members which may optionally be secured permanently at a window opening or which may be removably fitted therein. If removably fitted therein a number of advantages will suggest themselves, as for example, the entire unit may be removed to facilitate painting of the surrounding structure.

A further object resides in the resilient suspension of the sashes in the supporting members. The resilient suspension renders the sashes easily removable when desired, as when painting the surrounding structure, or to permit maximum ventilation. Also, minor variations in sizes of the sashes relative to the window opening are compensated by the resilient suspension as are seasonal variations in sizes of window openings resulting from alternately damp and dry conditions.

The invention is particularly adaptable to and apprehends metal construction. The use of non-corroding metals renders painting unnecessary, and the window frames may outlast the life of the supporting building structure. Additionally, the various members are individually secured or fitted in the window openings. Thus they may easily be cut to fit a window opening of a given size, facilitating installation.

These, and other objects of this invention will become apparent from an understanding of the following written description as illustrated in the accompanying drawings wherein

Fig. 1 is a plan view of the installed window construction, partially broken away, viewing the window from the interior of the building;

Fig. 2 is a fragmentary sectional perspective view, partly broken away to illustrate the juncture of the sashes;

Fig. 3 is a broken, sectional side elevation;

Fig. 4 is a fragmentary sectional view taken substantially on line 4—4 of Fig. 1; and

2

Fig. 5 is an exploded fragmentary perspective view of details of the invention.

The window comprises a pair of rectangular, vertically slidable sashes which may be referred to as top sash 2 and bottom sash 3, as they appear in Fig. 1. The said sashes are substantially identical in structure, with one exception, as hereinafter noted. Each sash may be provided with a rectangular pane 5 having on each edge a channel-shaped, metallic, protective strip, the protective strips of the top and bottom sashes being designated respectively as 2a and 3a. One flange 4 of each strip is shorter than the other flange 6. A wooden strip 7 is disposed in the bottom of the channels between the flanges, substantially flush with the inner edge of said shorter flange 4. The flanges 4 and 6 are spaced from each other a distance substantially equal to the thickness of standard window panes. The pane-receiving members 2a are jointed as best illustrated in Fig. 5 and are secured to each other at their corners, as by rivets 10a passing through the strips 2a and 3a and the enclosed wooden strip 7, to form the top sash 2, and with the short flanges 4 unilateral and the long flanges 6 unilateral. The pane-receiving members 3a are similarly secured together to form the bottom sash 3. The window pane 5 is secured in each sash by the segment of the long flange 6 protruding above the wooden strip 7 and being secured on the other side by glazier's points (not illustrated) inserted in the wooden strips and a suitable glazing compound 15.

The upper member of each sash is provided with knobs 8 to facilitate vertical adjustment of the sashes. The said knobs 8 are horizontally slidably mounted and project outwardly through enlarged slots 8a on the interior side of the top sash members. The knobs 8 are secured to spring biased latch members, not illustrated. The latches 30 releasably engage spaced apertures (not illustrated) in the jambs 9. For construction and operation of the said latch members reference is made to my Patent 2,288,936.

A pair of jambs 9 each define in cross section a shallow channel, centrally divided by a ridge or parting strip 10. The distances between each leg 9a and the parting strip of the jamb is substantially equal to the cross sectional thickness of a sash and such that each jamb 9 defines a pair of guides 11 and 12 slidably receiving a sash on either side of the parting strip 10. The guides will be referred to respectively as top and bottom sash receiving guides 11 and 12.

A pair of horizontally opposed, relatively deep channels 13 each having a cross sectional width substantially equal to that of the jambs 9 to slidably receive the jambs 9. A plurality of helical compression springs 14 are secured at spaced intervals to the interior surface of the web 13a of each channel 13, and resiliently bias jambs 9 outwardly toward snug engagement with sashes 2 and 3, but facilitate sliding of the sashes.

Again referring to the sashes 2 and 3, the lower member 2A of the top sash 2 (as in Figs. 1 and 2) is deformed adjacent the top of its longer flange 6 to define a V-shaped protuberance 16. The said protuberance 16 extends substantially the length of said lower sash member 2a of the top sash 2. The apex 16a of the V-shaped protuberance 16 extends horizontally from the lower sash member 2A a distance substantially equal to the cross sectional dimensions of the parting strip 10 of the jambs 9.

A top and bottom weather strip 17 and 18 are each longitudinally deformed to define in cross section an S including a fourth or reinforcing leg 19 which is folded back parallel and in close proximity to the adjacent leg of the S shaped strip. This cross sectional formation, illustrated in Figs. 3 and 5, provides a snug, sash receiving recess 21. The cross sectional width of each said weather

strip should be substantially the same as that of the channels 13.

The composition of the foregoing members is preferably metal. Non-corroding metals such as brass or aluminum are particularly suitable. Metals which normally corrode when exposed may also be satisfactorily employed if treated with an anticorrosive.

The unit may be installed in a window opening in a wall, in a door, or other location in a building structure where a window is desired.

The members may be easily cut with a metal saw. They should be cut to approximately the following lengths; the channels 13 and jambs 9 should be substantially the same lengths as the window opening; the weather strips 17 and 18 should be shorter than the width of the window opening by substantially twice the depth of the channels; the sashes 2 and 3 should be slightly wider than the weather strips and approximately one half the height of the window opening. The resilient installation will compensate for minor variations in size of sashes relative to the window opening.

The channels 13 are vertically secured in the frame wall to open toward each other. They may be rigidly secured in place, as by screws or nails driven through web 13a, or they may be removably secured between strips of spaced molding.

A jamb 9 is then temporarily manually biased against the compression springs and within a channel.

The bottom weather strip 18 is inserted at the bottom of the window opening between the jambs 9 abutting the bottoms of the latter. The said bottom weather strip 18 is positioned with its reinforcing leg 19 interior relative to the rest of the weather strip 18 and with its sash receiving recess 21 opening upwardly and in vertical alignment with the bottom sash or guides 11. The top weather strip is oppositely disposed between the tops of the jambs 9, i. e., such that its reinforcing leg 19 is exterior relative to the rest of the top weather strip 17 and with its sash receiving recess 21 opening downwardly and aligned with the top sash guides 12.

Similar to the channels 13, the weather strips may be secured in position by nails or screws. Or they may be removably disposed between spaced strips of molding.

The jambs 9 are now secured in position being biased between the weather strips 17 and 18 on one side and the compression springs 14 on the other.

The sashes may now be secured in place.

Assuming the window is being installed from the inside of the building, the top sash 2 is preferably inserted first. One edge of the top sash is fitted into a top sash guide 12 of one of the jambs 9 with the V protuberance 16 at the bottom of the sash and toward the worker. The sash is forced against the top sash guide in which it is fitted, forcing the jamb outwardly and so the other side of the sash may clear the interior guide 11 and the parting strip 10 of the other jamb to fit into the top sash guide of the other jamb.

The bottom sash is similarly installed in the interior guides 11 of the jambs.

The sashes may now be moved vertically in their respective guides. When closed, that is, when the top sash 2 is moved as far as it will go into the sash receiving recess 21 of the top weather strip 17, and the bottom sash 3 is moved as far as it will go into the bottom weather strip 18, the V protuberance 16 spans the distance between the horizontally spaced sashes, providing a substantially weather tight juncture. The sash receiving recess 21 of the top and bottom weather strips similarly render the unit weather tight at the top and bottom, as do the sashes fitted in the guides at the sides of the unit.

The top and bottom sashes may be lowered or raised for ventilation. If maximum ventilation is desired the sashes may easily be removed by pressing each sash against a jamb in order that the other side of the sash may clear the other jamb. If the weather strip and channels are secured in place only by spaced molding strips

they may easily be removed to facilitate painting of the surrounding structure.

Although the foregoing invention has been described in some detail by way of illustration and example for purposes of clarity of understanding, it is understood that certain changes and modifications may be practiced within the spirit of the invention and scope of the appended claims.

What is claimed is:

10. A window construction comprising a top sash, a bottom sash, protective strips around the margins of said sashes on both outer faces of said sash, side jambs at the sides of said sashes confining movement thereof to substantially parallel sliding movement in spaced paths, a bottom weather strip extending between said side jambs at the bottom thereof, and a top weather strip extending between said side jambs at the top thereof; each said weather strip having a cross-sectional shape consisting of a first and a second channel, each said first channel being of a width substantially equal to the thickness of said sashes including said protective strips, each said second channel being of a width substantially equal to the thickness of said sashes including said protective strips, plus the distance between sashes, said channels facing in opposite directions having a common side, said first channels facing inwardly, the first channel of one said strip being outermost and of the other said strip being innermost, and a reinforcing leg bent back substantially parallel and in close proximity to the side of said first channel, the outermost leg of said channel and said reinforcing leg terminating at the elevation of the bottom of said first channel, said bottom weather strip being positioned with its first channel directly underlying said bottom sash to seal against the outer faces of the protective strips along the bottom margin of said bottom sash when in closed position, said top weather strip being positioned with its first channel directly overlying said top sash to seal against the outer faces of the protective strips along the top margin of said top sash when in closed position.
20. 2. A window construction comprising a top sash, a bottom sash, protective strips around the margins of said sashes on both outer faces of said sash, side panels at the sides of said sashes confining movement thereof to substantially parallel sliding movement in spaced paths, a bottom weather strip extending between said side jambs at the bottom thereof, a top weather strip extending between said side jambs at the top thereof; each said weather strip having a cross-sectional shape consisting of a first and a second channel, each said first channel being of a width substantially equal to the thickness of said sashes including said protective strips, each said second channel being of a width substantially equal to the thickness of said sashes including said protective strips plus the distance between sashes, said channels facing in opposite directions having a common side, said first channels facing inwardly, the first channel of one said strip being outermost and of the other said strip being innermost, and a reinforcing leg bent back substantially parallel and in close proximity to the side of said first channel, the outermost leg of said second channel and said reinforcing leg terminating at the elevation of the bottom of said first channel, said bottom weather strip being positioned with its first channel directly underlying said bottom sash to seal against the outer faces of the protective strips along the bottom margin of said bottom sash when in closed position, said top weather strip being positioned with its first channel directly overlying said top sash to seal against the outer faces of the protective strips along the top margin of said top sash when in closed position.
30. 3. A window construction comprising a top sash, a bottom sash, protective strips around the margins of said sashes on both outer faces of said sash, side panels at the sides of said sashes confining movement thereof to substantially parallel sliding movement in spaced paths, a bottom weather strip extending between said side jambs at the bottom thereof, a top weather strip extending between said side jambs at the top thereof; each said weather strip having a cross-sectional shape consisting of a first and a second channel, each said first channel being of a width substantially equal to the thickness of said sashes including said protective strips, each said second channel being of a width substantially equal to the thickness of said sashes including said protective strips plus the distance between sashes, said channels facing in opposite directions having a common side, said first channels facing inwardly, the first channel of one said strip being outermost and of the other said strip being innermost, and a reinforcing leg bent back substantially parallel and in close proximity to the side of said first channel, the outermost leg of said second channel and said reinforcing leg terminating at the elevation of the bottom of said first channel, said bottom weather strip being positioned with its first channel directly underlying said bottom sash to seal against the outer faces of the protective strips along the bottom margin of said bottom sash when in closed position, said top weather strip being positioned with its first channel directly overlying said top sash to seal against the outer faces of the protective strips along the top margin of said top sash when in closed position.
40. 4. A window construction comprising a top sash, a bottom sash, protective strips around the margins of said sashes on both outer faces of said sash, side panels at the sides of said sashes confining movement thereof to substantially parallel sliding movement in spaced paths, a bottom weather strip extending between said side jambs at the bottom thereof, a top weather strip extending between said side jambs at the top thereof; each said weather strip having a cross-sectional shape consisting of a first and a second channel, each said first channel being of a width substantially equal to the thickness of said sashes including said protective strips, each said second channel being of a width substantially equal to the thickness of said sashes including said protective strips plus the distance between sashes, said channels facing in opposite directions having a common side, said first channels facing inwardly, the first channel of one said strip being outermost and of the other said strip being innermost, and a reinforcing leg bent back substantially parallel and in close proximity to the side of said first channel, the outermost leg of said second channel and said reinforcing leg terminating at the elevation of the bottom of said first channel, said bottom weather strip being positioned with its first channel directly underlying said bottom sash to seal against the outer faces of the protective strips along the bottom margin of said bottom sash when in closed position, said top weather strip being positioned with its first channel directly overlying said top sash to seal against the outer faces of the protective strips along the top margin of said top sash when in closed position.
50. 5. A window construction comprising a top sash, a bottom sash, protective strips around the margins of said sashes on both outer faces of said sash, side panels at the sides of said sashes confining movement thereof to substantially parallel sliding movement in spaced paths, a bottom weather strip extending between said side jambs at the bottom thereof, a top weather strip extending between said side jambs at the top thereof; each said weather strip having a cross-sectional shape consisting of a first and a second channel, each said first channel being of a width substantially equal to the thickness of said sashes including said protective strips, each said second channel being of a width substantially equal to the thickness of said sashes including said protective strips plus the distance between sashes, said channels facing in opposite directions having a common side, said first channels facing inwardly, the first channel of one said strip being outermost and of the other said strip being innermost, and a reinforcing leg bent back substantially parallel and in close proximity to the side of said first channel, the outermost leg of said second channel and said reinforcing leg terminating at the elevation of the bottom of said first channel, said bottom weather strip being positioned with its first channel directly underlying said bottom sash to seal against the outer faces of the protective strips along the bottom margin of said bottom sash when in closed position, said top weather strip being positioned with its first channel directly overlying said top sash to seal against the outer faces of the protective strips along the top margin of said top sash when in closed position.
60. 6. A window construction comprising a top sash, a bottom sash, protective strips around the margins of said sashes on both outer faces of said sash, side panels at the sides of said sashes confining movement thereof to substantially parallel sliding movement in spaced paths, a bottom weather strip extending between said side jambs at the bottom thereof, a top weather strip extending between said side jambs at the top thereof; each said weather strip having a cross-sectional shape consisting of a first and a second channel, each said first channel being of a width substantially equal to the thickness of said sashes including said protective strips, each said second channel being of a width substantially equal to the thickness of said sashes including said protective strips plus the distance between sashes, said channels facing in opposite directions having a common side, said first channels facing inwardly, the first channel of one said strip being outermost and of the other said strip being innermost, and a reinforcing leg bent back substantially parallel and in close proximity to the side of said first channel, the outermost leg of said second channel and said reinforcing leg terminating at the elevation of the bottom of said first channel, said bottom weather strip being positioned with its first channel directly underlying said bottom sash to seal against the outer faces of the protective strips along the bottom margin of said bottom sash when in closed position, said top weather strip being positioned with its first channel directly overlying said top sash to seal against the outer faces of the protective strips along the top margin of said top sash when in closed position.
70. 7. A window construction comprising a top sash, a bottom sash, protective strips around the margins of said sashes on both outer faces of said sash, side panels at the sides of said sashes confining movement thereof to substantially parallel sliding movement in spaced paths, a bottom weather strip extending between said side jambs at the bottom thereof, a top weather strip extending between said side jambs at the top thereof; each said weather strip having a cross-sectional shape consisting of a first and a second channel, each said first channel being of a width substantially equal to the thickness of said sashes including said protective strips, each said second channel being of a width substantially equal to the thickness of said sashes including said protective strips plus the distance between sashes, said channels facing in opposite directions having a common side, said first channels facing inwardly, the first channel of one said strip being outermost and of the other said strip being innermost, and a reinforcing leg bent back substantially parallel and in close proximity to the side of said first channel, the outermost leg of said second channel and said reinforcing leg terminating at the elevation of the bottom of said first channel, said bottom weather strip being positioned with its first channel directly underlying said bottom sash to seal against the outer faces of the protective strips along the bottom margin of said bottom sash when in closed position, said top weather strip being positioned with its first channel directly overlying said top sash to seal against the outer faces of the protective strips along the top margin of said top sash when in closed position; and a V-shaped protuberance formed on the inner edge of a protective strip along the inner margin of one of said sashes, said protuberance being formed on the face of its sash facing the opposite sash and of a magnitude slightly greater than the distance between the spaced paths of said sashes.

said protuberance sealing against the adjacent protective strips of the opposite sash when both said sashes are in closed position.
